UNITED STATES PATENT OFFICE.

JOHN EDMUND EAGLES, OF NEW WESTMINSTER, BRITISH COLUMBIA, CANADA.

LANDING PLATFORM FOR FLYING MACHINES.

Application filed August 23, 1923. Serial No. 658,935.

To all whom it may concern:

Be it known that I, JOHN EDMUND EAGLES, a subject of the King of Great Britain, and a resident of the city of New Westminster, in the Province of British Columbia, Canada, have invented certain new and useful Improvements in Landing Platforms for Flying Machines, of which the following is a specification.

10 My invention relates to improvements in landing platforms for flying machines, and the object of my invention is to devise a landing platform the use of which enables the machine to be readily and easily controlled from the moment it arrives within a certain distance from the platform until it comes to a stop and which further provides for the stoppage of the machine positively within a certain defined limit so that the 20 landing of an aeroplane, hydroplane, or other type of flying machine is rendered a matter of absolute certainty and safety.

I attain this object by the construction illustrated in the accompanying drawings 25 in which—

Fig. 1 is a fragmentary view showing part of the underbody of a flying machine with the platform-contacting member assembled thereon.

20 Fig. 2 is a side elevation of a vessel illustrating the landing platform arrangement.

Fig. 3 is a plan view of Fig. 2.

Fig. 4 is a front end view of a machine and the platform-contacting member.

30 Fig. 5 is a diagrammatic view of the electro-magnetic circuit control arrangement.

Fig. 6 is a sectional detail view of a spring bumper.

40 Similar figures of reference indicate similar parts throughout the several views.

According to my invention, taking for illustration a vessel having an aeroplane as part of its equipment so that space on the 45 deck is provided for manoeuvring, or a floating hangar 1 of the type projected and in construction, where the top deck 2 is flush from stem to stern, a metal platform 3 is arranged at the spot where the machine is 50 destined to land and this platform is of a width sufficient to receive the wheels of the plane and long enough to provide sufficient run to enable the plane to be brought to rest thereon. This platform is connected to 55 a source of electric current through wires 4, controlled by a suitable controller 5 so

that the current can be increased step by step and the current is arranged to pass in any well-known manner through suitable coils disposed under the platform so that 60 when the current is switched on the platform becomes magnetized, the arrangement being such that the magnetic field may be increased in strength gradually from one end of the platform to the other end. It 65 will be readily understood that any well-known electro-magnetic means may be employed to magnetize the platform.

Secured to the flying machine 6 on its underbody towards its opposite sides are two 70 housings 7 and 8 each containing a coil spring 9 through each of which springs extends longitudinally a rod 10 and 11 respectively, these rods extending at one end exteriorly of the housing and having this end 75 eyed, these ends being indicated by the numerals 12 and 13, so that there may be swingably connected thereto wooden arms, 14 and 15 respectively, while the opposite end of each rod lies within its respective housing 80 and is enlarged as at 16 so that the end of the spring bears against it. Thus, the spring in each housing bears at one end against one end of the housing and at its other end against the rod enlargement, so that 85 each housing contains in effect a spring bumper by means of which each wooden arm is resiliently supported and thus the risk of damage to the arms through shock is eliminated to a great extent. The wooden 90 arms lead aft and their opposite ends converge and to the converging ends is secured a metal platform-contacting member 17 which is thereby disposed on the longitudinal axis of the machine, since the arms 95 converge centrally, and as the arms are swingably connected to the bumper rods they may be swung up to lie against the underbody of the machine when the latter is in the air and this is effected by means 100 of a cable 18 connected at one end to the wooden arms 14 and 15 and led through suitable pulleys and connected at its opposite end to a suitable gripping member in the cockpit, which arrangement will be 105 readily understood without any detailed illustration or description. A latch device 19 of any approved make is used to hold the arms in the upwardly swung position. When the arms are in the downmost position the metal contacting member supported 110 by them is on a lower level than that of the

wheels so that when the machine is landing the member is the first part of the machine to contact.

Thus, a machine coming to land, heads 5 for the landing platform and on approaching the same drops the arms to the full extent so that the metal contacting member 17 contacts with the end of the metal landing platform 3 which is magnetized by 10 current switched on by an operator handling the controller 5. The magnetic strength of the platform, however, is only strong enough at this point to check the machine but as the machine travels along above the 15 platform, with the contact member 17 trailing thereon the operator gradually increases the strength of the current until the magnetic strength of the platform is such that the contact member is held firmly thereto 20 and thus the machine can go no further and is thereby brought to rest without jar or shock and with great safety to both the machine and its occupants so that risk of accident and damage and also loss of life is 25 eliminated.

It will thus be seen that I have devised a useful and practical means of great utility for the landing of flying machines which 30 consists in brief of a platform capable of being magnetized with gradually increasing force from one end to the other, the magnetic strength being directed to the retarding and holding of a metal contacting element 35 carried by the machine which is dropped into the contacting position when the machine nears the landing platform.

What I claim as my invention is:—

1. A landing device for flying machines comprising, a suitably supported platform

capable of being magnetized, a pair of arms 40 hingedly connected at their forward ends to the underside of the plane body whereby they may be raised against or lowered away from the same and converging at their rear ends, and a platform-contacting element secured to the rear ends of the arms adapted to be attracted to the platform when brought within the field of magnetic influence 45 of the same.

2. A landing device for flying machines 50 comprising, a suitably supported platform capable of being magnetized, a pair of arms hingedly connected at their forward ends to the underside of the plane body whereby they may be raised against or lowered away 55 from the same and converging at their rear ends, a platform-contacting element secured to the rear ends of said arms adapted to be attracted to the platform when brought within the field of magnetic influence of the 60 same, means for raising or lowering the said arms, and means for supporting the arms in the raised position.

3. A landing device for flying machines 65 comprising, a suitably supported platform capable of being magnetized, a pair of laterally spaced bumper rods secured to the underside of the plane body, a pair of arms hingedly connected at their forward ends to the rear ends of said bumper rods converging 70 at their rear ends, and a platform-contacting element secured to the rear ends of the said arms adapted to be attracted to the platform when brought within the field of magnetic influence of the same. 75

Dated at Vancouver, B. C., this 3rd day of August, 1923.

JOHN EDMUND EAGLES.
